UNITED STATES PATENT OFFICE.

ALFRED A. SPADONE, OF NEW YORK, N. Y., ASSIGNOR TO THE GUTTA PERCHA & RUBBER COMPANY, OF NEW YORK, N. Y., A CORPORATION OF NEW YORK.

DESIGN FOR TILING.

No. 38,580.

Specification for Design.

Patented May 21, 1907.

Application filed April 2, 1907. Serial No. 366,050. Term of patent 14 years.

To all whom it may concern:

Be it known that I, ALFRED A. SPADONE, a citizen of the United States, and a resident of the borough of Manhattan, city, county, and State of New York, have invented a new, original, and ornamental Design for Tiling, of which the following is a specification.

The accompanying drawing shows a face view of my new design.

I claim:

The ornamental design for tiling as shown.

ALFRED A. SPADONE.
